METHOD AND APPARATUS FOR PRODUCING
RADIO BEACONSPaul J. Holmes, Los Angeles, Calif., assignor to
William H. Donnelly, Los Angeles, Calif.

Application April 17, 1939, Serial No. 268,172

8 Claims. (Cl. 250—11)

This invention relates to methods and apparatus for providing radio beacon courses.

Systems have been previously proposed which use a single pair of vertical radiators which radiate an identifiable signal in accordance with one lobular horizontal directivity pattern when fed in one phase relation and another identifiable signal in accordance with a second pattern overlapping the first pattern when fed in another phase relation. The two overlapping patterns thus provide equi-signal radio beacon courses. The phase changing in the currents supplied to the radiators has heretofore been accomplished through the use of mechanical or electromechanical switching arrangements. This introduces complications which increase the cost of construction and maintenance.

A particular object of this invention is to provide simple methods and apparatus for producing a plurality of directive radio beacon courses with two spaced radiators by changing the phase of the currents at the radiators by purely electrical means and without using any mechanical or electromechanical switching arrangements for phase changing.

Another object of the invention is to provide methods and apparatus for producing a multi-course directive radio beacon which will produce visual or aural indications or a combination thereof along with code or voice communication.

A further object of the invention is to provide simple methods and apparatus for producing directive radio beacon courses which use suppressed carrier transmission and resupply the carrier frequency to the transmitted signal in space.

According to this invention I supply a wave resulting from modulation of a carrier wave of given frequency to the first side of a phase-shifting network which has a radiator connected thereto. I also supply a wave resulting from modulation of a carrier wave of the same given frequency to the second side of said network which has a radiator connected thereto, which radiator is spaced from said first-named radiator. Each of said supplied waves may comprise, for example, a modulated carrier wave including both side bands, or it may comprise the two side bands from which the carrier wave has been suppressed, or it may comprise a single side band from which the carrier and the other side band has been suppressed. Said waves supplied to the opposite sides of said network may result from modulation by the same modulation frequency or they may result from modulation by two different and preferably audible modulation fre-

quencies. The phase relation between the waves radiated at each of said radiators determines the horizontal directivity pattern of the combined wave radiated by said radiators and due to the phase shifting network between said radiators and the manner in which waves are supplied to said radiators and to said network, the phase relation between the radiated waves is periodically shifted causing the radiators to radiate periodically changing horizontal directivity patterns. As brought out subsequently, these patterns may be made identifiable in such manner as to provide equisignal radio beacon courses.

We may assume for the purposes of illustration that amplitude modulated waves are directly supplied to the opposite sides of the network and are of the same amplitude, and that one wave is modulated by one audio frequency modulation signal and the other by a different audio frequency modulation signal and that the carriers of said waves are in phase upon their arrival at the network. As the two waves go through their cyclic changes in amplitude at the opposite sides of the network, there will be instants of time in which the two waves are of equal amplitude and other instants in which one wave has a finite amplitude while the other is zero and still other instants in which said other wave has a finite amplitude and said one wave is zero. Assuming for the sake of simplicity that a wave traveling from either side of the network to the radiator connected to that side undergoes the same phase shift (although this is not necessary as will be brought out subsequently), it may be seen that the radiators radiate in phase when the waves are of equal amplitude and out of phase by the amount of phase shift provided by the phase-shifting network, say 90°, when either one of the waves is at zero and the other wave has a finite amplitude. The directivity pattern produced when one wave has zero amplitude and the other wave has a finite amplitude is similar to the pattern radiated when the reverse relation between the two waves is obtained; however, the two patterns are reversed in space since the phase shift applied to each wave is additive. By proper spacing of the radiators, preferably more than one-fourth the carrier frequency wavelength, say three-fourths the wavelength, the two patterns overlap. One of these overlapping patterns is due primarily to one of the modulated waves and the other is primarily due to the other modulated wave. Hence in the zones where the patterns overlap the two signals are radiated with equal intensity and pro-

vide equi-signal radio beacon courses. In the intervals of time between the in phase radiation and the 90° out of phase radiation, the radiation pattern changes through successive patterns from the in phase pattern to the 90° out of phase pattern to produce one set of patterns and vice versa. One set of patterns is produced predominantly by the action of one of the modulated waves and the other is produced predominantly by the action of the other of the modulated waves.

As brought out above, I may radiate the carrier and both side bands from the above-mentioned radiators or I may suppress the carrier and radiate only one or both the side bands. In the latter cases I resupply the carrier to the radiated waves by radiation from a non-directive third radiator which radiates the carrier in the proper time phase relationship. This last system has some advantages in that the resupplied carrier may also be modulated by voice or code signals for communication purposes.

Further objects of my invention will become apparent when my invention is described in conjunction with the accompanying drawings in which:

Fig. 1 is a diagrammatic illustration of a simple form of my invention;

Figs. 2, 3, and 4 are horizontal directivity patterns which may be obtained with the apparatus illustrated in Fig. 1;

Fig. 5 is a diagrammatic illustration of a modified form of my invention;

Fig. 6 illustrates horizontal directivity patterns which may be obtained with the apparatus illustrated in Fig. 5; and

Fig. 7 is a diagrammatic illustration of a receiving apparatus which may be used to identify the beacon courses provided by the apparatus shown in Figs. 1 and 5.

Referring to Fig. 1, a suitable carrier power source such as a master oscillator 10 oscillating at any desired frequency, say 3 megacycles, is shown connected to modulators 11 and 12 which are respectively connected to power amplifiers 13 and 14. The modulators 11 and 12 preferably amplitude modulate the radio frequency carrier with different and distinct audio frequency modulation signals, say 65 and 86.7 cycles, so that the amplitude modulated waves delivered thereby may be separately identifiable after radiation. For reasons which will appear later the modulators preferably operate to produce 100% modulation of the carrier. The power amplifiers 13 and 14 are shown connected respectively to transmission lines 15 and 16 leading to different sides of a phase-shifting network 17 operable to produce a phase-shift of 90°, for example, in the current traversing the phase-shifting network. The remaining ends of the transmission lines 15 and 16 are shown connected through suitable coupling networks 18 and 19 to radiators 20 and 21 respectively. The radiators 20 and 21 may comprise vertical radiators having a length comparable to one-quarter of the wavelength of the carrier frequency supplied by the master oscillator 10 and the two radiators 20 and 21 may be spaced horizontally from one another by any convenient distance, preferably greater than a distance equal to one-quarter the carrier wavelength, for example, by a distance of about three-quarters of a carrier wavelength.

The amplitude modulated waves delivered by the power amplifiers 13 and 14 are separately identifiable, and for the purposes of illustration it may be assumed that the carrier frequency

contained in each of these modulated waves is delivered in phase to the opposite sides of the phase-shifter 17. This may be accomplished by introducing suitable phase-shifting networks in either one or both of the branch circuits leading from the power amplifiers 13 and 14 as shown at 13a and 14a, if required. Also, in the interests of clarity, we may assume that the amplitudes of the modulated waves delivered by the power amplifiers 13 and 14 are equal.

At a given instant of time and at the opposite sides of the network 17, the 65-cycle modulated wave may have a maximum amplitude, while the 86.7-cycle wave may have zero amplitude. At this instant, assuming that currents supplied by the amplifiers 13 and 14 are in phase at the opposite sides of the phase-shifter 17, radiation from both antennae 20 and 21 will be due to power amplifier 13 which is modulated by the 65-cycle tone. Due to the action of the phase-shifting network 17, currents radiated from the radiator 21 will be 90° out of phase with currents radiated from the radiator 20, assuming that characteristics of the transmission lines 15 and 16 and coupling devices 18 and 19 are the same. This will cause the radiators to radiate predominantly a 65-cycle wave in accordance with a lobular horizontal directivity pattern, as shown in full lines at 30 in Fig. 2.

In Figs. 2, 3, and 4 the radiators 20 and 21 are located on a horizontally extending line R—R, symmetrically disposed with respect to the centers of the circles surrounding the directivity patterns illustrated in said figures. The patterns are plotted in polar coordinates to represent the relative amplitudes of the radiated signals as transmitted in any horizontal direction from the centers of the circles at distances which are great compared to the distances between the radiators 20 and 21.

At some later instant of time, the amplitude of the 65-cycle modulated wave delivered by power amplifier 13 will be somewhat less than maximum, but will still be somewhat greater than the amplitude of the 86.7-cycle modulated wave delivered by the power amplifier 14 to the opposite side of the phase-shifting network 17, which last-named wave is now greater than zero and is approaching its maximum. As a consequence, the resultant currents radiated by the antennae 20 and 21 will be somewhat less than 90° out of phase, for example about 45° out of phase, and will be radiated in accordance with a lobular horizontal directivity pattern as shown in full lines at 31 in Fig. 3. This pattern, like the pattern 30, will still be separately identifiable since it results primarily from the radiation of a 65-cycle modulated wave.

As the 65-cycle modulated wave continues to diminish in magnitude and the 86.7-cycle modulated wave continues to increase in magnitude, the lobular pattern as shown in full lines at 30 and 31 in Figs. 2 and 3 becomes more nearly symmetrical with respect to a line perpendicular to the line R—R and becomes symmetrical with respect to said perpendicular line when the two waves are of equal amplitude and the resultant currents at the radiators are in phase, as shown in full lines at 32 in Fig. 4. The pattern illustrated at 32 exists only for an instant and then the 86.7-cycle modulated wave delivered by the amplifier 14 has a greater amplitude than the 65-cycle modulated wave delivered by the amplifier 13. Since the amplitude relation is now opposite to that described above, the phase-shift

is effectively in the opposite direction so that the full-line pattern 31 which was due predominantly to the 65-cycle modulation is now reversed in space, assuming that the relative phase difference between the resultant currents at the two radiators is the same as it was, say about 45°. This reversed pattern is shown in dotted line at 31a in Fig. 3 and is primarily due to the 86.7-cycle modulation. The patterns 31 and 31a are shown overlapping in six places so as to provide six equi-signal courses 33, 34, 35, 36, 37, and 38. Along these courses the 86.7-cycle and 65-cycle modulated waves may be heard with equal average intensity.

As the 86.7-cycle modulated wave increases in magnitude and the 65-cycle modulated wave goes to a minimum, the maximum phase-shift between the resultant waves radiated by the two radiators 20 and 21 will occur again. At this time the 86.7-cycle modulated wave has maximum amplitude and the 65-cycle modulated wave has minimum amplitude. At this time the radiation will be totally due to the power amplifier 14 which is modulated with an 86.7-cycle tone, and the directivity pattern will be the same as the pattern 30 except that it will be reversed in space as shown in dotted lines at 30a. The overlap of the patterns 30 and 30a corresponds practically to the overlap of the patterns 31 and 31a so that the courses defined thereby will correspond practically to the courses 33, 34, 35, 36, 37, and 38.

Thus the phase between the resultant currents at the radiators will be shifted first in one direction and then in the other to provide first one set of lobular horizontal directivity patterns and a second set of lobular horizontal directivity patterns similar to the first set of patterns but reversed in space and overlapping the first patterns. This shifting in the patterns is accomplished through the use of purely electrical means without the use of any mechanical or electromechanical switching apparatus.

Directivity patterns such as those shown in Figs. 2 and 3 will be radiated more often and persist longer than the pattern shown in Fig. 4. Thus the equi-signal zones defining the beacon courses will be readily recognizable even though signals are radiated according to the pattern illustrated in Fig. 4 for relatively short periods during each cycle of operation when the two modulated waves have equal amplitudes.

In the example above described, in the areas between courses 33 and 34, 35 and 36, and 37 and 38, an 86.7-cycle signal will be received with greater average intensity than a 65-cycle signal. In the remaining areas, that is, the areas between courses 34 and 35, 36 and 37, and 38 and 33, the 65-cycle signal will be received with greater average intensity than the 86.7-cycle signal. This provides a useful form of quadrant course identification. For example, an airplane flying away from the line R—R in the general direction of course 33 when provided with proper receiving equipment can easily identify courses 33 and 38, since a deviation to the right on course 38 will result in an increase in the relative intensity of the 65-cycle signal while a deviation to the right on course 33 will result in an increase in the relative intensity of the 86.7-cycle signal.

It is not necessary that the modulated waves supplied to the respective radiators be modulated by different selected audio frequency modulation signals, since the waves may also be made separately identifiable even though they are modu-

lated by the same selected audio frequency modulation signal. For example, the modulators 11 and 12 may each supply the same 1000-cycle modulation signal, for example, to the waves supplied to the power amplifiers 13 and 14. In order to separately identify the modulated signals, the signal supplied by the modulator 11, for example, may be interrupted with one code sequence and the other may be interrupted with a second code sequence which is time-interlocked with the first code sequence. For example, the modulations supplied by 11 may be interrupted in an A manner (dot-dash) and the modulations supplied by 12 in an interlocking N manner (dash-dot), as is well known to the art, so that in the equi-signal zones defining the beacon courses a steady tone is received. An example of an apparatus for coding the modulation is illustrated diagrammatically in Fig. 5. On one side of a course the A signal is received with greater intensity than the N signal, and on the other side of a course the N signal is received with greater intensity than the A signal. Under such conditions one of the modulators will be operating when the other is not supplying a signal and vice versa. Thus, when the modulator 11 is operating for example, the directivity pattern 30 will be obtained, while when the modulator 12 is operating the directivity pattern 30a will be obtained and the radiation will shift rapidly from the pattern 30 to the pattern 30a without passing through the remaining intermediate patterns shown in Figs. 3 and 4.

Obviously, other radiator spacings besides three-fourths wavelength can be used. Also other phase shifts besides 90° can be used. The particular spacing and phase shift depend upon the number and direction of courses required, as well as on the vertical directivity patterns obtained. The horizontal directivity patterns for numerous spacings and phase relations are illustrated in the Radio Engineering Handbook, second edition, McGraw-Hill Book Co., 1935, so that the spacings and phase relations for a given set of conditions may be readily determined. When using the arrangement shown in Fig. 1 it is desirable to modulate both the 65 and 86.7 waves 100% in order to get the maximum phase difference between the currents radiated.

In Fig. 5 I have illustrated a form of my invention adapted to provide aural and visual beacon course indications as well as voice or telegraphic communication. A carrier frequency source 40 oscillating at any desired frequency, say three megacycles, is shown connected to balanced modulators 41 and 42. A 65-cycle modulation source 43 is shown connected to the balanced modulator 41, and an 86.7-cycle modulation source 44 is shown connected to the balanced modulator 42. Thus, the modulator 41 delivers carrier-suppressed 65-cycle modulated waves to amplifier 45, and balanced modulator 42 delivers carrier-suppressed 86.7-cycle modulated waves to amplifier 46. The amplified waves from the amplifiers 45 and 46 are fed through lines 45a and 46a to opposite sides of a phase-shifting network 47 adapted to produce any desired phase shift, for example 90°, in currents traversing the network. Spaced radiators 48 and 50, such as vertical radiators having a length on the order of one-quarter the carrier frequency wavelength and spaced from one another by distances on the order of one-half the carrier frequency wavelength, are shown connected through suitable coupling networks 51 and 52 to transmission lines 53 and 54

which are connected to opposite sides of the phase-shifting network 47 and also to amplifiers 45 and 46 respectively. Another phase shifting network 47a, giving a phase shift of 90° for example, is shown connected in the transmission line 53 between the coupling device 51 and the lines 45a.

In the arrangement illustrated in Fig. 5, only the side bands of the 65- and 86.7-cycle waves are radiated from the radiators 49 and 50, since the carrier in each of the waves has been suppressed at the balanced modulators 41 and 42. In order to resupply the carrier frequency to the side bands radiated from 49 and 50, I may provide a non-directional radiator 55, such as another vertical radiator comparable to the radiators 49 and 50 located centrally, for example, with respect to the radiators 49 and 50. The radiator 55 is shown connected through a phase-shifter 56 and amplifiers 57 and 58 to the source of carrier frequency 40. The phase-shifter 56 is provided to correct the phase of the carrier supplied to the radiator 55 so that the radiated carrier will have the proper time-phase relationship with respect to the side bands radiated from 49 and 50, which relation is well known to the art. The use of a suppressed carrier not only permits increased efficiency and a saving in power, but also provides a communication channel, since the resupplied carrier radiated by the radiator 55 may be modulated by voice or with other forms of intelligence. The modulated amplifier 58 is provided for this purpose.

In order to simplify the description we may assume that the resulting carrier components due to the side bands delivered by the amplifiers 45 and 46 are made to arrive at the opposite sides of the phase-shifting network 47 either in phase or in phase opposition. Since the two waves result from modulation by different modulation frequencies and because the carrier has been suppressed, the relation between the carrier components of the two waves is periodically shifted 180°. The phase between the waves arriving at the network 47 may be adjusted by inserting suitable phase-shifting networks, if required, in either one or both of the lines 45a and 46a after the manner of the networks 13a and 14a shown in Fig. 1.

In order to illustrate the relations which bring about the overlapping identifiable space patterns that produce the radio beacon courses, it is only necessary to consider the patterns radiated when one of the supplied waves has zero amplitude and the other wave has a finite amplitude. When the wave due to the 86.7-cycle modulation has zero amplitude and the wave due to the 65-cycle modulation has finite amplitude, the 65-cycle modulated wave is radiated in phase from the radiators 49 and 50, since it travels through the network 47 in going to the radiator 50 and through a similar network 47a in going to the radiator 49. The horizontal directivity pattern for radiation in phase is indicated by the full line pattern 60 in Fig. 6. When the 65-cycle modulated wave has zero amplitude and the 86.7-cycle modulated wave has finite amplitude, the 86.7-cycle modulated wave is radiated in phase opposition from the radiators 49 and 50 to produce the horizontal directivity pattern shown in dotted lines at 61 in Fig. 6. The wave traveling to the radiator 50 goes directly thereto while the wave traveling to the radiator 49 undergoes two 90° phase shifts due to phase shifters 47 and 47a thereby causing the radiators 49 and 50 to radi-

ate 180° out of phase or in phase opposition. The patterns 60 and 61 are shown intersecting at four points to produce courses 62, 63, 64, and 65 along which the 65- and 86.7-cycle tones can be heard with equal average intensities.

In Fig. 6 the radiators 49 and 50 are located on a horizontally extending line R—R and symmetrically disposed with respect to the centers of the circle surrounding the directivity patterns illustrated in said figure. The patterns are plotted in polar coordinates to represent the relative amplitudes of the radiated signals as transmitted in any horizontal direction from the centers of the circles at distances which are great compared to the distance between the radiators 49 and 50.

The 65- and 86.7-cycle signals are best adapted for visual course indications, as will be described more completely hereinafter, and I may also provide aural course indications as by modulating the carrier in both of the modulators with a suitable modulation signal, for example 1000 cycles, as applied by modulation source 67 which is connected to both the balanced modulators 41 and 42 through a coding switch 68 operated by a conventional code wheel illustrated diagrammatically at 69.

The code wheel may be rotating in the direction of the arrow A and is shown provided with raised portions 70 separated by indented portions 71. The switch 68 is provided with a follower 72 adapted to follow the contour of the code wheel 69 so that the switch 68 makes contact with a fixed contact 73 when the follower 72 is riding on the raised surfaces 70 of the code wheel. At this time the 1000-cycle modulation is supplied only to the balanced modulator 42. When the follower 72 is in contact with the indented portions 71 of the code wheel, the arm 68 establishes connection with another fixed contact 74 so that the 1000-cycle modulation is supplied only to the balanced modulator 41. By inspection of Fig. 5, it may be seen that as the wheel 69 rotates, the code letter A will be impressed upon the wave supplied by the amplifier 45 and the code letter N will be impressed upon the wave supplied by the amplifier 46. It will also be seen that the two letters are interlocked so that they will be received as a substantially continuous 1000-cycle tone on the courses 62, 63, 64, and 65, and as either an A or an N in the areas between the courses.

When using the suppressed carrier arrangement illustrated in Fig. 5 it is not necessary to modulate the carrier 100% in order to realize the maximum phase shift of the phase-shifting network connected between the radiators as it is with the arrangement in Fig. 1. For example, I may provide only 30% modulation with each of the 65 and 86.7 modulation waves and add thereto a 30% modulation from the 1000-cycle coded wave. The resupplied carrier may also be modulated by the voice modulator 58 by another 30%, for example. Although the arithmetic sum of all the modulations supplied to either one of the waves may be more than 100%, the actual modulation is still less than 100%, due to the relation of the waves when they are recombined in space.

Obviously, spacings and phase-shifts other than those described in connection with Fig. 5 may be employed to give the desired number of courses, as will be apparent to one skilled in the art, by employing the principles detailed herein. It must be remembered, however, that

although the horizontal directivity patterns produced by many combinations of radiator spacing and phase shift appear satisfactory, the vertical directivity of the arrangement must also be considered. The arrangements illustrated are satisfactory from both horizontal and vertical directivity considerations.

An example apparatus which may be carried by a mobile body such as an airplane for following the beacons provided by the apparatus shown in Figs. 1 and 5 is illustrated diagrammatically in Fig. 7. A conventional radio receiver 81 is shown with its output connected to magnet coils 84 and 85 located adjacent to tuned magnetic reeds 86 and 87 which are adapted to vibrate at 65 and 86.7 cycles when the coils of the magnets 84 and 85 are energized by currents of those frequencies. Thus a visual indication of the relative magnitudes of the received 65 and 86.7 cycles may be obtained by observing the amplitude of vibration of the reeds 86 and 87. An on-course heading may be indicated when the reeds 86 and 87 vibrate with equal amplitude, and when one reed vibrates with greater amplitude than the other the airplane is known to be located in either a 65- or 86.7-cycle zone. Aural indications of position, when using the apparatus illustrated in Fig. 5, may be obtained by connecting the output of the receiver 81 to a tuned filter 88 tuned to 1000 cycles for example and provided with a suitable indicating instrument such as a pair of headphones 89. An off-course position is represented by either an A-tone or an N-tone, while an on-course position is indicated by a continuous 1000-cycle note.

When using the modulated amplifier 58 to send intelligence such as voice over the system illustrated in Fig. 5, I may provide the radio receiver with a filter 90 which is adapted to pass frequencies from about 200 to about 2000 cycles per second while rejecting the 1000 cycle frequency so that voice or other intelligence may be heard through earphones 91 without interference from the other fixed tones used in the beacon system. Obviously, the receiving apparatus, as well as the transmitting apparatus, is subject to wide modification. For example, I may modulate the amplifiers 11 and 12 in Fig. 1 with 750 and 1000 cycles instead of the 65 and 86.7 cycles as illustrated, in which case the reeds 86 and 87 would be tuned to 750 and 1000 cycles and the filter 88 would be adapted to pass the 750- and 1000-cycle signals so that aural as well as visual indications could be obtained. Under such circumstances the filter 90 and receiver 91 could be eliminated.

The patterns shown in Figs. 2, 3, 4, and 6 are those obtained when the currents at the two radiators are equal. When the ratio of the currents at two radiators is other than unity the patterns will be shifted with respect to the line R—R about the centers of the circles enclosing the patterns. Under such circumstances the resulting courses will make different angles with one another than shown in said figures. Obviously, the resulting courses can be oriented by changing the ratio of the currents supplied to the radiators by means well known to the art.

Throughout the specification and in the appended claims the term "wave resulting from modulation of a carrier" is intended to include substantially continuous as well as interrupted waves. Substantially continuous waves include envelopes resulting from modulation in which the amplitudes of the envelopes pass momen-

5 tarily through zero, and intermittent waves include such envelopes which remain at zero for a finite length of time.

My invention as described in relation to the above illustrative examples is subject to wide modification, and hence I do not choose to be limited to the examples described herein, but rather to the scope of the appended claims.

I claim:

1. In the production of a radio beacon through the agency of a pair of spaced radiators connected to the opposite sides of a phase-shifting network, the steps of producing a first wave from amplitude modulation of a carrier of given frequency with a first continuous audio frequency signal and with an intermittent coded signal of a second audio frequency while suppressing the carrier; producing a second wave from amplitude modulation of a carrier of said given frequency with a third continuous audio frequency signal and with an intermittent coded signal of said second frequency while suppressing the carrier; said coded signals being applied in interlocking sequence; continuously supplying said first wave to one of said sides of said network; continuously supplying said second wave to the other of said sides of said network; and radiating the resultant waves from said radiators.

2. A method as set forth in claim 1, which includes the steps of modulating a carrier of said

30 given frequency with a communication signal; and radiating said last-named modulated car-

35 rier from a non-directional third radiator in

proper phase to resupply the carrier to said re-

sultant radiated envelopes.

3. In a radio beacon, the combination which comprises: a pair of balanced modulators; a source of carrier waves connected to said modulators; means for supplying different modulation frequencies to the respective modulators; a first phase-shifting network having one side connected to receive the output from one of said modulators and its other side connected to receive the output from the other of said modulators; a radiator connected to one of said sides of said network; a second radiator; and a second phase-shifting network connected between said second radiator and the other of said sides of said network.

4. An apparatus as set forth in claim 3, in which said networks each produce a phase shift of about 90° at the carrier wave frequency and said radiators are spaced about one-half a car-

50 rier wavelength.

5. An apparatus as set forth in claim 3, which further comprises means for supplying a modulation signal of a third audio frequency alternately to both of said modulators in an inter-

60 locking coded sequence.

6. An apparatus as set forth in claim 3, which further comprises means including a non-directional third radiator for radiating said carrier wave in proper phase relationship to combine with the waves radiated from said first-named radiators.

7. In the production of a radio beacon through the agency of a pair of spaced radiators connected to the opposite sides of a phase-shifting network, the steps of amplitude modulating a carrier with two different audio frequency signals to thereby produce two separate waves each resulting from a different one of such modulations, said waves resulting from suppressed carrier modulation; continuously supplying one of

said waves to one of said sides of said network and continuously supplying the other of said waves to the other of said sides of said network; radiating the resultant waves from said radiators; and resupplying the carrier to said radiated resultant waves in space in proper phase relationship by radiation from a non-directional third radiator.

8. In a radio beacon, the combination which comprises: a phase-shifting network having first and second sides; a source of carrier waves connected to said first and second sides of said network; means continuously connected between

said source and said first side of said network for modulating said carrier with an audio frequency signal; means continuously connected between said source and said second side of said network for modulating said carrier with a different audio frequency signal; and a pair of spaced radiators connected respectively to the first and second sides of said network; said network producing a phase shift of about 90° at the carrier frequency and said radiators being spaced about three-quarters of a carrier wavelength from one another.

PAUL J. HOLMES.
